UNITED STATES PATENT OFFICE.

E. H. HULL, OF MILLERSBURG, OHIO.

IMPROVED SUBMARINE SHOT-CONDUCTOR.

Specification forming part of Letters Patent No. 44,631, dated October 11, 1864.

To all whom it may concern:

Be it known that I, E. H. HULL, of Millersburg, in the county of Holmes, in the State of Ohio, have invented a new and improved mode of firing through water; and I do hereby declare that the following is a full and exact description thereof, reference being had to the accompanying drawings, and to the letters of reference marked thereon.

The nature of my invention consists in inserting into the side, bow, or stern of a vessel, below the water-line, a tube of any required length and of any permanent material, having a bore somewhat longer than that of the gun used in connection therewith, said tube being provided at the outer end with a valve of india-rubber or other flexible material, and of such form and construction as to allow a ball or projectile fired from the interior of the vessel through the tube to make its exit, and at the same time to exclude the water.

To enable others skilled in the art to make and use my invention, I will proceed to describe its construction and operation.

I first construct a tube, A, Figure 1, of any required length and of any permanent material, having a bore somewhat larger than that of the gun used. I insert said tube into the side, bow, or stern of a vessel, having it surrounded at the point of insertion by a section or packing of india-rubber, B, Fig. 1, said section or packing being so firmly and securely attached to the vessel as to constitute a perfect water tight joint. Said tube A is permanently secured to the gun-carriage J, inside the vessel, in such a manner and position that it will be at all times in range with the gun, leaving a space between for vent, as shown at H, Fig. 1. To the outer end of said tube I attach a water-proof valve, G, of india-rubber or other flexible material, the same being provided with a metallic lining, which is divided into sections, each of which is firmly

attached to the end of the tube A by means of a hinge. The aforesaid valve G is of such peculiar form and construction that a ball or projectile fired from the gun C through the tube A will readily make its exit, as shown at D, Fig. 2.

Fig. 2 is a sectional view of the interior of the valve and metallic lining, of which E is a section of the hinge by which the several sections F F F of the metallic lining are secured to the end of the tube A. The valve G is secured firmly around and over the end of the tube and metallic lining, said valve being divided into sections I I I, corresponding in number and size with those of the metallic lining.

The operation of this invention is conducted as follows: When the gun has been charged ready for action, the carriage is run forward, thereby causing the tube to slide through the india-rubber section or packing and protrude to any desired length. The gun is then fired, when the ball passes through the tube and through the valve, which thereupon immediately closes, thereby excluding the water. The carriage may then be run back again to its former position for another charge.

The object of this invention is to facilitate the operation of firing through water, by means of which an enemy's vessel may be attacked at the most vulnerable points below the water's line.

What I claim as my invention, and desire to secure by Letters Patent, is—

The tube A and valve G, together with the metallic lining F F F, when arranged and operating in the manner and for the purpose described.

E. H. HULL.
